UNITED STATES PATENT OFFICE.

CHARLES F. PRESSLER, OF FORT WAYNE, INDIANA.

LIQUID-MEASURING PUMP.

1,328,101.

Specification of Letters Patent. Patented Jan. 13, 1920.

Application filed August 9, 1917. Serial No. 185,279.

To all whom it may concern:

Be it known that I, CHARLES F. PRESSLER, a citizen of the United States, residing at Fort Wayne, in the county of Allen and 5 State of Indiana, have invented new and useful Improvements in Liquid-Measuring Pumps, of which the following is a specification.

The invention relates to improvements in 10 liquid measuring pumps.

The object of the invention is to provide a continuous flow pump, such as the pump described in my prior Letters Patent No. 913,848 dated March 2, 1909, with an electric motor driving means and with novel 15 means for accurately measuring the fluid delivered by the pump.

In the drawings I illustrate one manner in which the invention may be carried out in 20 which—

Figure 1 is a side elevation of mechanism constructed according to my invention, the case being in section and fractional and the pump being fractional.

Fig. 2 is a plan view of the main gear.

Fig. 3 is a rear elevational view of the main gear.

Fig. 4 is a plan view of the motor-driven worm and lever support therefor.

Fig. 5 is a front elevational view of the measuring dial.

Fig. 6 is a side elevational view of the plunger, the plunger lock and lock releasing mechanism.

Fig. 7 is a fractional longitudinal sectional view of the plunger lock, and

Fig. 8 is an end elevational view of the plunger lock.

Referring to the exemplification of the invention in the drawings the entire mechanism will be inclosed preferably in a case, indicated by 10, so that the mechanism may be installed outside as well as inside a building for vending liquid such as gasoline, the 45 door of the case, of course, being locked to prevent unauthorized access to the mechanism. 11 indicates a double acting cylinder, the piston rod 12 of its piston being connected to crank 13 on revolute shaft 14 borne by frame 15. Piston rod 16 connected to crank 17 on shaft 14 is also connected to the piston of an auxiliary cylinder 18 having connection with cylinder 11. Cylinders 11 and 18 are described in my prior Patent 50 No. 913,848. Gear-wheel 19 is secured to shaft 14 between cranks 13 and 17. If preferred the piston rods may be connected to

the gear. An annular slot 20 is provided in the inner face of gear 19 near its periphery and pins 21 are passed at selected points 60 through the gear and slot and project beyond the inner face of the gear.

A ratchet 22 secured to the lower end of shaft 23 is adapted to be abutted and rotated by the pins. Gear 24 secured to the 65 upper end of shaft 23 meshes with gear 25 secured to shaft 26, which shaft drives the totaling register 27 which indicates the total quantity of liquid delivered by the pump during any selected period of time. Worm 70 28 is secured to shaft 23 and drives gear 29 secured to hub 30 of ratchet 31 (Fig. 6), which hub is revolutely mounted on spindle 32 projecting laterally from bracket 33. A hub 31^b on the forward face of ratchet 31 75 has a split sleeve 31^a projecting forwardly from it upon which sleeve is a tapering washer 35. Nut 35^a on the end of spindle 32 when tightened drives the washer on the split sleeve and clamps it to spindle 32. 80 Ratchet 31 is thereby secured to the spindle. Index or hand 34 is loosely mounted on hub 31^b and has free movement thereon. A latch bolt 36 is slidably supported by two apertured lugs 36^a on the rear face of the index, 85 spring 36^b tending to force the upper end of the bolt between two teeth of ratchet 31 and lock the index to the ratchet. Button 37 is threaded to stud 36^c secured to bolt 36 which extends through a slot in index 34 and serves 90 as means for withdrawing the bolt from engagement with the ratchet when it is desired to manually shift the index upon hub 31^b as hereafter described. For continuous pumping bolt 36 is withdrawn from 95 ratchet 31 and button 37 is tightened against the face of index 34 to hold the bolt. A dial 38 is suitably supported on casing 10, as by posts 38^a, and is provided with two series of graduations adjacent the outer and inner 100 peripheries of the ring respectively. These graduations represent gallons, half gallons, quarts and pints, the inner set being numbered clockwise and the outer set counter-clockwise. The inner set is used to measure 105 the quantity of liquid required to fill a container where the container is to be filled and the amount of liquid required is not known or given and the outer set of graduations is used where a certain quantity of liquid is 110 desired by the user or purchaser. These operations will be more fully explained hereinafter.

For driving gear 19 I have provided a

worm gear 39 adapted to mesh with gear 19 and secured to shaft 40, revolubly mounted at one end in a suitable bearing 41 secured to lever 42 and at its other end in bracket 43 5 secured to or integral with lever 42. Gear 44 is secured to shaft 40 and is in mesh with gear 45 secured to shaft 46 borne by bracket 43. Gear 47 secured to shaft 46 is in mesh with gear 48 secured to shaft 49 of electric 10 motor 50. The motor is mounted on lever 42 and at suitable points on the lever adjacent the motor are two brackets 51 which are pivoted at 52 to case 10. The pivotal points of the lever are so located that when 15 the lever is rocked toward gear 19 worm 39 will be moved in proper manner to cause its teeth to engage the teeth of gear 19 without injury to the teeth of either; that is, the worm is moved radially to the gear.

20 A slotted lug 53 depends from lever 42 and pin 53^a carried by the frame or casing 10 projects into the slotted lug for supporting the lever when the device is inoperative. Link 54 is connected at one end to the free 25 end of lever 42 and at its other end it is connected to crank 55 secured to a suitably supported shaft 56. Link 57 is connected to shaft 56 and to a clamp 57^a, in which clamp plunger 58 is reciprocably mounted. 30 Spring 58^a on the plunger tends to maintain it in its outer position. The inner end of plunger 58 is reciprocably supported in opening 59 in block 60 and adjacent its end is a peripheral notch 61. Block 60 is fixed 35 immediately in front of the 0 graduations on dial 38 and a stop 62 is provided on the adjacent face of the block by boss 62 which is integral with the block and projects rearwardly from the rear face thereof. A locking plate 63 is pivoted at 64 to this face of 40 the block and covers a portion of opening 59. It also extends above stop 62, a spring plunger 65 carried by stop 62 tending to separate the plate and stop and maintain the plate in its normal position. When 45 plunger 58 is forced inwardly toward the dial its notched end forces the depending portion of the locking plate away from stop 62 and compresses spring plunger 65. As soon as notch 61 registers with the edge of 50 plate 63, spring plunger 65 forces the plate into the notch and thereby the plunger is locked in its inner position. When the plunger is pushed inwardly lever 42, by 55 means of the connecting links and crank, is elevated on its pivots and worm 39 is connected to gear 19.

A plate 66 is pivoted at 67 to plate 63 and carries a suitable handle 68 by which it may 60 be rocked on its pivot to the left (Fig. 8) to a horizontal position. The upper end of plate 66 overlaps plate 63 so that it has no movement to the right (Fig. 8) independently of plate 63. A ball and spring 66^a is 65 provided in plate 66 which bears against

plate 63 and produces sufficient friction between the two plates to maintain plate 66 in upright position. The lower end of index 34 is adapted to abut the upper portion of plate 66 as it approaches the 0 graduation 70 on the dial and to rock the plate together with plate 63 to the right (Fig. 8) to release plunger 58, whereupon spring 58^a on the plunger restores the plunger to its normal outer position and worm 39 is disconnected from gear 19. The releasing devices for the plunger are effective when a certain quantity of liquid is to be pumped. 75

In order that the electric motor shall operate only when the delivery of liquid is desired I provide a knife switch 70, the circuit between the terminals or leaves 71 and 72 of which is closed by member 73 mounted on and insulated from lever 42. When the lever is rocked toward gear 19 contact member 73 enters between leaves 71, 72 before worm 39 engages gear 19 so that the motor has started to operate and worm 39 is beginning its rotation as it meets gear 19 thereby insuring easy engagement of the worm and gear. 80

Leaf 71 of switch 70 is connected by wire 74 with binding post 75 of the motor and leaf 72 is connected to a switch 76 within the casing, the switch 76 being also connected to one side of the main supply circuit. The other binding post 77 of the motor is connected by wire 78 to the main supply circuit. 95

In operation if the owner desires to fill 100 a tank of unknown capacity he places the index on 0 and turns latch plate 66 to the horizontal position by swinging it to the left (Fig. 8), to remove it from the path of index 34. Switch 76 is closed and 105 plunger 58 is pushed inwardly until plate 63 snaps into notch 61 to lock the plunger. The movement of the plunger is transmitted to lever 42 to cause the electrical circuit to the motor to be closed at switch 70 by contact member 73 on lever 42 and to engage worm 39 and gear 19. As the gear is rotated its pins drive ratchet 22 and shaft 23 intermittently for rotating ratchet 31 and the index clockwise. When the tank is full 110 switch 76 is thrown to cut-out the motor and the quantity of liquid pumped into it is read on the inner series of graduations on the dial. Plunger 58 is released by elevating plate 66 to its normal vertical position 115 and rocking it and plate 63 to the right, (Fig. 8).

When a predetermined quantity of liquid is desired the index is placed over the corresponding graduation of the outer series on 125 the dial and plate 66 is placed in its normal vertical position if not already in that position and the plunger is pushed in as before. The index travels over the dial toward the 0 graduation and as it approaches 0 it meets 130

plate 66 and rocks it and plate 63 to automatically release the plunger. Whereupon the worm 39 disengages from gear 19 and the motor circuit is broken at switch 70, 5 and the pump almost instantly stops. The quantity of liquid pumped will be found to correspond to that indicated upon the dial in the one case and to that for which the index was set in the second case.

10 It is obvious that the several gear ratios and sizes and arrangement of the parts may be varied to suit conditions, the embodiment of the invention above described being only an illustration of a convenient arrangement.

15 What I claim is:

1. The combination with a pump mechanism, of a pivotally supported driving mechanism adapted to be connected to the pump mechanism, means to cause the two mechanisms to engage, means to lock said mechanisms in engagement, means having an operative connection to one of said mechanisms for automatically releasing the engagement 25 of said mechanisms, and means to control the operation of the driving mechanism.

2. The combination with a pump mechanism, of a pivotally supported driving mechanism adapted to be connected to the pump mechanism, means to cause the two mechanisms to engage, means to lock said mechanisms in engagement, means having an operative connection to one of said mechanisms for automatically releasing the engagement 35 of said mechanisms upon the delivery by the pump mechanism of a predetermined quantity of liquid, and means to control the operation of the driving mechanism.

3. The combination with a pump mechanism, of a pivotally supported electrically driven member adapted to be connected to the pump mechanism for operating the same, means to cause the driven member to engage the pump mechanism, means to lock the 45 said engagement of said driven member and pump mechanism, means to release the said engagement of the driven member and the pump mechanism when the pump mechanism has delivered a selected quantity of 50 liquid, and means to control the operation of the driven member.

4. The combination with a continuous flow pump mechanism, of a pivotally supported electrically driven worm adapted to be connected to the pump mechanism for operating the same, means to move the worm into engagement with the pump mechanism, means to control the operation of the worm 55 and means to disconnect the worm from the pump mechanism when the latter has delivered a selected quantity of liquid.

5. The combination with a continuous flow

pump mechanism, of a worm, an electric motor to rotate the worm, means to control the electric motor and to shift the worm into engagement with the pump mechanism, a graduated scale and means for causing the worm to automatically disengage from the pump mechanism, said means being adjustable relatively to the scale and having an operative connection to the pump mechanism. 65

6. The combination with a continuous flow pump mechanism, of an electrically driven member adapted to drive the pump mechanism, a pivotally mounted support for the 70 driven member, a switch for the electrically driven member adapted to be closed by the movement of the support, a spring opposed plunger having connection with the support for causing the driven member to engage the 75 pump mechanism, means to lock the plunger after the engagement of the driven member and pump mechanism, and means to automatically release the plunger upon the delivery by the pump mechanism of a selected 80 quantity of liquid for causing the driven member to disengage from the pump mechanism 85 and the switch to be opened.

7. The combination with a pump mechanism, of a pivotally supported means to 90 drive the pump mechanism, means to lock the driving means to the pump mechanism, means to release the driving means from the pump mechanism, a dial having two 95 series of graduations thereon, an adjustable revolvably mounted index to coöperate with the dial for indicating on one of said series of graduations the quantity of liquid delivered by the pump mechanism and by adjustment with respect to the other of said graduations for predetermining the quantity of 100 fluid to be pumped by the pump mechanism, and means to rotate the index.

8. The combination with a pump mechanism, of a pivotally supported means for 105 driving the pump mechanism normally disconnected therefrom, means to connect the driving means to the pump mechanism, means to lock the latter connection, means to release the driving means from its connection with the pump mechanism consisting of an adjustable revolvably mounted index, a ratchet having connection with the index 110 and adapted to be rotated by the pump mechanism, the index being adapted to abut the locking means for releasing it upon the delivery by the pump mechanism of a pre-determined quantity of liquid, and a graduated scale indicating quantities of liquid 115 over which the index is moved.

120 In witness whereof I hereunto subscribe my name this 7th day of August, 1917.

CHARLES F. PRESSLER.
